UNITED STATES PATENT OFFICE

ALBERT F. BEMIS, OF NEWTON, MASSACHUSETTS, ASSIGNOR TO BEMIS INDUSTRIES, INC., OF BOSTON, MASSACHUSETTS, A CORPORATION OF DELAWARE

BUILDING CONSTRUCTION

Application filed April 3, 1928. Serial No. 266,955.

This invention relates to an improved form of building construction, and more particularly to a structural framework and the arrangement of the same in conjunction with 5 related parts.

One aspect of the present invention relates to the provision of improved frame members, each of which preferably are formed of a plurality of structural elements which may be 10 so assembled and arranged as to provide a frame member so that the fastening means at wall intersections may lie without the plane of one of the intersecting walls, thus affording means which permits the more convenient 15 assembly of the structural framework and the more convenient application of the subsequent finish thereto. Further objects of the invention relate to structural features of the frame members which cooperate with each 20 other to provide connections which may be readily assembled.

Furthermore, the present arrangement lends itself to the provision of parts formed with standardized dimensions with means to engage fastenings or other building parts located at modular distances, so that the frame members may be manufactured in 25 quantities in an establishment particularly adapted for the purpose and may be rapidly 30 assembled in situ without the requirement of a high degree of skill or particular accuracy upon the part of the workmen.

The above and further objects and advantageous features of the invention will be apparent to those skilled in the art upon a reading of the subjoined description and claims in conjunction with the accompanying drawings, in which:

40 Fig. 1 is a sectional view of the lower portion of a wall assembly under construction;

Fig. 2 is a section on line 2—2 of Fig. 1;

Fig. 3 is a perspective view of the assembly at the intersection of a vertical and a horizontal wall, for example, between a vertical wall 45 and a floor;

Figs. 4, 5 and 6 are similar views of other forms of the invention;

Fig. 7 is a side view of wall;

50 Fig. 8 is a section through the same; and

Fig. 9 is a perspective detail showing a part of a post assembly.

In the accompanying drawings, the numeral 1 indicates a portion of the footing upon which the foundation of a building is 55 to be formed, the first story being erected above this foundation. According to one method of constructing a building embodying the improvements provided by the present invention, plates 2 are first secured to the 60 foundation 1 at approximately the positions to be occupied by the central portions of the vertical posts. The vertical posts, designated by numerals 3 and 4 in Figs. 1 and 2, may be built up of a plurality of channels 5 with 65 their legs outstanding in planes at right angles or in alignment with each other. When a post is to be located at the corner formed by walls in two intersecting planes, as shown at the right of Fig. 2, one channel is provided to 70 receive the ends of the frame members for each of the planes; thus two channels are provided with their bight portions at right angles to each other, while if the walls are to cross each other, as shown to the left of Fig. 75 2, channels are provided at all four sides of the post. At the upper and lower ends of the posts I may provide suitable fastening members 7 to secure the channels to each other. These members are formed of a central portion 8 having an intermediate opening 9 adapted loosely to engage an anchor plate 2. Plate portions 10 are bent up at right angles to the central portion 8 and are secured to the bight portions of the vertically disposed 80 channels. Thus the vertical posts are built up of two, three or four channels 5 with their bight portions held in engagement with flanges 10 of a fastening member 7 at the upper and lower ends of the post. 90

In order to assist in properly locating the posts and particularly in holding their upper ends in proper position, I make use of one of the standardized girt members 12 which may be afterwards disposed between the upper 95 portions of the same posts. Thus the girt 12 has a length which accurately determines the spacing of the posts 3, and accordingly it first may be used for properly positioning the lower ends of these posts after the man- 100

ner shown in Figs. 1 and 2. It is to be understood that the girt member 12 is provided with openings 14 spaced at modular distances, which are subsequently to be used for engagement with adjoining parts of the structure. One of these openings 14 adjoining each end of the member is temporarily engaged with a bracing member 15 which may have a hooked lower portion 16 engaging the edge of the opening and which may 10 comprise similar diagonal bar portions 17 having their upper ends secured to the adjoining vertical wall of a post 3 by the adjustable and detachable fastening elements 18 which may take the form of nuts or the like, although obviously a turnbuckle may be arranged in the intermediate portion of each of the bars 17 in order to effect suitable adjustment of the parts. The temporary 15 angles 20 preferably are arranged to connect member 12 to the posts, and the fastening elements 18 are then suitably adjusted to bring the upper ends of the posts in proper position so that the girt or sill member 22 for the first story may be accurately located 20 between the posts. This girt may be secured in place by fastening means 23 which may be similar to the angles 20 or which may be of any other desired form. After the posts 25 have thus been connected, preferably by two or more permanently located girts, the lower girt 12, which has temporarily served as a spacing and aligning member, may be removed and concrete may be poured below 30 the sill member 22 and between or about the lower portions of posts 3 to provide a foundation. Subsequently girt member 12 may be used as a girt for a subsequent story, for example at the top of the second story.

Fig. 3 illustrates one method in which a girt of this type is connected to the adjoining wall structure and shows more particularly the construction of such a girt. This frame member preferably is built up of similar structural elements 30 which may be in the form of channels having surfaces upon their bight portions in juxtaposed parallelism and in abutting engagement with an intermediate spacer plate or web member 33. Preferably the legs of the channels are provided with inturned flanges 35, as shown. The spacer plate 33 preferably has a depth greater than the depth of the adjoining structural elements so that it provides a longitudinal flange 34 upon at least one side of girt 12. Preferably this flange is provided with openings 35 spaced at modular distances and adapted to receive suitable fastening means.

As shown in Fig. 3 a girt of this character 60 may be combined with wall units 36 of the character disclosed in my copending application Serial No. 72,675, filed December 2, 1925, these units being arranged with suitable, vertically disposed spaces 37 which are 65 adapted to register with openings 14 within

the intermediate portion of the girt to permit the pouring of concrete 31 into the upper channel 30 with integral extensions thereof located within spaces 37 to provide vertical reinforcements for the walls. The floor 70 joists 40 may be disposed upon the flange 34, being secured thereto by fastening elements 41 passing through the openings 35 and engaging the lower portions of the joists as shown.

Fig. 4 shows a similar frame member arranged with a flange 34 at each side thereof, thus being adapted to be located in an intermediate partition which supports horizontal walls such as floors at each of its sides. The 80 floor joists 40^a, shown in Fig. 4, are disposed in the same general manner as described above but are here shown as being formed of metal. In this form of the invention suitable studs 50 are arranged with end portions of reduced size, designated by numeral 51, engaged within each of the channels 30 and with surfaces 52 juxtaposed to inturned flanges 35. The ends of these studs are preferably held in place by means of wedges 53 85 driven through openings 14 at each side of the studs and in engagement with opposite faces thereof.

Fig. 5 illustrates an optional form of the invention, wherein the girt 60 is formed of similar channels 61 with inturned aligned flanges 62 upon their legs and with an intermediate plate 63 disposed between juxtaposed parallel faces of the channels which are arranged back to back. Preferably this plate has a greater depth than the channels to provide longitudinal flanges 65 both at the top and bottom of the frame member. In this embodiment of the invention, it is evident that the intermediate spacer plate is vertically disposed or, in other words, the frame member is disposed in a plane at right angles to that shown in Figs. 3 and 4. With this form of the invention, pairs of openings 66 may be arranged at modular distances in the flanges 65 and may receive wedges 67 which engage opposite faces of studs 68, the latter being slotted, as designated by numeral 69, to have end portions straddling the longitudinal flange. In Fig. 5 another means for 1 securing floor joists 70 to girt 60 is shown, the joist having a tongue portion 71 received within the channel by angle elements 72 which engage the face of the channel and the joist.

Fig. 6 shows a girt 12 of the form disclosed in Figs. 3 and 4 with suitable connecting members 75 extending through the openings 14. The studs 150 preferably may be secured to the members 75, in such a manner as to permit the filling of the lower portion of member 12 with reinforcing material. For this purpose a metal channel 76 may be located within the lower channel 30 of member 12, being provided with openings of a suitable

size to permit members 75 to extend therethrough. The stud members 150 may then be secured to members 75, terminating below channel 76. A suitable space is left beside each of the members 75 in openings 14 to permit the pouring of cementitious material between channels 30 and 76. Subsequent to this pouring, the studs 150 for the succeeding story may be mounted above girt 12, being secured to members 75 by fastening elements 151, as shown. While I have illustrated wooden studs 150 used in this combination, it is obvious that metal studs may be equally suitable for this type of assembly. Thus girt 12 may be greatly strengthened and is adapted to support the entire weight of the wall without necessity for dependence upon the intermediate stud elements. Fig. 6 also illustrates another means of securing the floor joists upon the flange 35. In this form of the invention the end of the joist 86 is provided with a slot 87, and suitable bracing straps 89 are located at either side of the joist 86 having one end in engagement with a flange 34 and secured to one of the openings within the flange and having its other end secured to the vertical face of the joist 86.

Fig. 6 also discloses a slightly different member for securing the post elements to each other. The post 30^a is here shown as provided with a capping member 100 having outstanding flanges 101 to rest above the post channels and having downwardly extending flanges 102 interfitted with the end of the post and adapted to engage the bight portions of the channels which form the same.

Figs. 7 and 8 show a frame member 12 forming a span between supporting members such as the foundation 1 and post 90 and supporting a wall thereabove. To this end suitable form boards may be located below the lower channel 30 and above either side of the frame member to receive poured cementitious material such as concrete. The openings 14 through the bight portions of the channels and the spacer plate 34 permit the poured material to fill the lower channel 30 reinforcing the same. The outstanding ledges 34 upon the member 12 may support suitable floor joists. It is evident that the concrete 93 within lower channels 30 forms a reinforcement for the frame member 12 and permits the same to support a wall having a considerable span between its supports.

Fig. 9 illustrates still another form of post end member which may be utilized in place of the members 8 or 102 previously described. This capping member is provided with an upper portion 104 substantially in the form of a hollow square with notched corner portions, which is adapted to rest upon the channels of the post member. The intermediate flanges 105 are formed by bending down the metal within the hollow square and are adapted to engage the bight portions of the

channels in order to hold them properly in place.

I claim:

1. A building construction comprising two walls in intersecting planes, a frame member extending along the line of intersection, said member comprising face parts clamping therebetween a projecting web part, frame members in one of said walls engaging said projecting web part and frame members in the other of said walls engaging one of said face parts. 70

2. A building construction comprising two walls in intersecting planes, a frame member extending along the line of intersection, said member comprising face parts clamping therebetween a web part projecting in the plane of one of said walls, which wall has frame members whose ends bear against the side of said web part, and frame members in 80 the other wall interlocking with one of said face parts. 85

3. A building construction comprising two walls in intersecting planes, a junction member extending along the line of intersection, 90 said member having an elongate recessed part and a web part extending longitudinally thereof and projecting laterally therefrom, frame members in one of said walls interlocked with said web part, and frame members in the other wall having their ends extending into the recess of said elongate part. 95

4. A building construction comprising two walls in intersecting planes, a frame member extending along the intersection of said 100 planes, said frame member comprising a pair of structural elements having juxtaposed faces, a spacing plate between said faces, said plate having a different depth from that of the juxtaposed faces, the frame elements in 105 one wall being connected with one of the structural elements of said frame member, the frame element in the other wall having an interfiting engagement with a portion of said frame member, the arrangement of said 110 spacing plate affording means for said interfiting engagement.

5. A building construction comprising two walls in intersecting planes, a frame member extending along the intersection of said 115 planes, said frame member comprising a pair of structural elements having juxtaposed faces, a spacing plate between said faces, said plate having a margin projecting beyond the structural elements to comprise a longitudinal flange, frame elements of one wall being secured to said flange and frame elements in the other wall engaging another portion of the frame member. 120

6. A building construction comprising two 125 walls in intersecting planes, a frame member extending along the intersection of said planes, said frame member comprising a pair of similar structural elements shaped to provide longitudinal recesses, said elements hav- 130

ing faces in juxtaposed parallelism, a spacing plate between said faces, said plate having a margin projecting beyond the structural elements to comprise a longitudinal flange, frame elements of one wall being secured to 5 said flange and frame elements in the other wall engaging another portion of the frame member.

7. A building construction comprising two 10 walls in intersecting planes, a frame member extending along the intersection of said planes, said frame member comprising a pair of structural channels having juxtaposed faces, a spacing plate between said faces, said 15 plate having a different depth from that of juxtaposed faces, the frame elements of one wall being received within one of said channels of the frame member, the frame elements in the other wall having an interfitting engagement with a portion of said frame member, the arrangement of said spacing plate 20 affording means for said interfitting engagement.

8. A building construction comprising two 25 walls in intersecting planes, a frame member extending along the intersection of said planes, said frame member comprising a pair of structural elements having juxtaposed faces, a spacing plate between said faces, said 30 plate having a different depth from that of the juxtaposed faces, frame elements of one wall being received within one of said elements of the frame member, frame elements in the other wall having an interfitting engagement with a portion of said frame member, the arrangement of said spacing plate 35 affording means for said interfitting engagement, and registering openings in the elements and web member for connection with a portion of the wall.

9. A building construction comprising two 45 walls in intersecting planes, a frame member extending along the intersection of the walls, said walls each having structural elements with one end connected to the frame member, at least a portion of the joint between the frame member and frame elements of one wall lying outwardly from that portion of the frame member which engages the ends of the 50 frame elements in the other wall.

10. A building construction comprising walls meeting at an angle, a structural element extending along the intersection of the walls, frame members in each wall connected to said structural element, and said element having along the length thereof parts 55 extending transversely of each wall for connection with the frame members of the other wall.

60 11. A building construction comprising walls meeting at an angle, a structural element extending along the intersection of the walls, frame members in each wall connected to said structural element, and said element 65 having along the length thereof parts extend-

ing laterally beyond the sides of the frame members of one wall, for connection with the frame members of the other wall.

12. A building construction comprising 70 walls meeting at an angle, a structural element extending along the intersection of the walls, frame members in each wall connected to said structural element, and said element having along the length thereof parts extending laterally beyond the sides of the frame members of each wall for connection with the frame members of the other wall.

75 13. A building construction comprising a vertical wall, a horizontal frame member in the same, said member comprising structural elements with parallel juxtaposed faces, a web plate between said faces and secured thereto, said plate projecting laterally beyond the structural elements to form a ledge, load supporting members disposed in a wall 80 at a plane at an angle to the vertical wall, said members resting upon the ledge.

85 14. A building construction comprising 90 two walls in intersecting planes, a frame member extending along the intersection of said planes, said member comprising a central web plate, similar structural elements having parallel faces secured to opposite faces of the plate and having flanges extending away from the plate, the latter having a margin 95 projecting laterally beyond the flanges to comprise a longitudinal ledge, frame elements of one wall being secured to said ledge, frame elements of the other wall being connected to another portion of the frame member.

100 15. A building construction comprising 105 two walls in intersecting planes, a frame member extending along the intersection of said planes, said member comprising a central web plate, similar structural elements having parallel faces secured to opposite faces of the plate and having flanges at each 110 side extending away from the plate adjoining each side of the frame member, the web plate having a margin projecting laterally beyond the flanges at one side of the frame member to comprise a longitudinal ledge, frame elements of one wall being secured to the ledge, frame elements of the other wall being disposed between the planes of the flanges at 115 opposite sides of the member and being secured to the latter.

16. A building construction comprising 120 two walls in intersecting planes, a frame member extending along the intersection of said planes, said member comprising a central web plate, similar structural elements having parallel faces secured to opposite faces of the plate and having flanges extending away from the plate adjoining each side of the frame 125 member, the web plate having a margin projecting laterally beyond the flanges at one side of the frame member to comprise a longitudinal ledge, frame elements on one wall being secured to the ledge, frame elements of the 130

other wall being disposed between the planes
of the flanges at opposite sides of the member
and being secured to the latter, and longitudi-
nally disposed, spaced openings in the por-
5 tion of the frame member between the flanges
to permit pouring of cementitious material
between the last-named frame elements.

Signed by me at Boston, Massachusetts,
this 17th day of February, 1928.

ALBERT F. BEMIS.
